UNITED STATES PATENT OFFICE

LEWIS MOORE AND CLAUDE M. DIBBLE, OF JOLIET, ILLINOIS, ASSIGNEES TO MOORE BROTHERS COMPANY, OF JOLIET, ILLINOIS, A CORPORATION OF ILLINOIS

REVERSIBLE STOVE AND FUEL CONNECTION

Application filed November 27, 1925. Serial No. 71,561.

This invention relates in general to stoves and connections therefor, and more particularly to reversible stoves and a connector for connecting a plurality of stoves to a common 5 fuel supply source.

An important object is to provide a stove, which may include two or more separate units, such as an oven part and a burner box part, or an oven and broiler part and a burner 10 box or other part, that may be connected together with either side of each to the other to provide a single stove having always the features and characteristics of the separate units without using special connector parts for 15 each form of assembly so that with any arrangement of the stove parts the connector may be arranged to suit the arrangement of the parts and connected to a single source of fuel supply.

Another object is to provide a connector 20 that may be used for connecting two or more stoves or the like to a single source of fuel supply which may be arranged to suit the arrangement of the stoves in a plurality of positions.

Another object is to provide a connector arrangeable to supply fuel to a plurality of stoves when arranged in two or more positions relative to each other, which may be as- 30 sembed of standard pipe fittings or the like.

Another object is to provide a stove includ- 35 ing two or more separate sections attachable to each other when arranged in two or more positions relative to each other to provide a single unit which may be secured together upon original assembly in any arrangement relative to each other, and which may be re- 40 versed or altered at any time thereafter without supplying new parts, and particularly the parts for conducting fuel to the burners in each of said parts.

Numerous other objects and advantages of 45 the invention will be apparent as it is better understood from the following description, which, taken in connection with the accompanying drawings, discloses a preferred embodiment thereof.

Referring to the drawings,

Figure 1 is a front elevation of a stove em- 50 bodying our invention;

Fig. 2 is a plan view of the device shown in Fig. 1;

Fig. 3 is a rear elevation of the device shown in Fig. 1, with parts thereof broken away and showing an arrangement of the preferred form of connector, and

Fig. 4 is a similar view showing the stove parts in reversed positions relative to each other and the connector adjusted to the arrangement.

To illustrate our invention, we have shown a stove including separate parts 11 and 12, legs 13 for supporting these parts, and a connector 14. The stove parts 11 and 12 may be arranged for any desirable purpose, and more such units may be added, if desired. In the present instance the part 11 is a burner box 60 unit having a plurality of heating plates 15 and control valves 16 for controlling the fuel supply to the heating plates 15. Each of the valves 16 is connected to a conductor 17, which extends to the back of the stove part for connection to a fuel supply source. The part 12 in the present instance includes an oven 18 and a broiler 19 also having suitable valves 21 65 connected into a conductor extending to the back of the stove for connection to a supply source.

While the parts 11 and 12 may be of any suitable form, they are preferably formed as shown and described in our copending application Serial No. 66,243, filed November 2, 1925, and so that they may be attached to each other and provided with legs 13, which may be of any suitable form and size for supporting the stove. They are also of a form to permit of attaching either part on either side of the other part so that any desired relative arrangement of the part may be had to provide a stove that will suit surrounding conditions or the personal characteristics of the user.

The connector 14 may be arranged to connect any number of the units 11 and 12 to a common source of fuel supply, which is indicated by the pipe or conductor 22, which may be attached to the connector at either end, as indicated in Fig. 4, the connector being shown in solid lines at one end and in dotted lines at the other.

It will be noted that after once assembling the stove and connecting it to the conductor or supply source 22, the parts 11 and 12 may be reversed without varying the point of connection with the conductor 22, so as not to require a change in the length thereof. In the present embodiment we have shown the supply pipes extending to the back of the stove parts at points near the side walls thereof. It will be noted, however, that they may extend to the back of the stove at any point. The connector 14 is joined with or connected to these pipes by elbows 23, which obviously may be adjusted to extend in any direction from the said pipes. The connector 14 includes a central duct which is made up of nipples 24 and 25, a pipe union 26 and a pair of T joints 27. The outside ends of the T joints provide a means of connection for the conductor 22, and, since only one such conductor is required, one of these ends may be closed with a pipe plug 28. Connecting arms extend out from the T joints 27 to the elbows 23, which form a part of the connector. These arms may include nipples 29 and 31, and elbows 32, or may be formed of a nipple 33 and an inside and outside elbow 34.

It will be noted that the connector 14, including the parts 23 to 29 and 31 to 34 inclusive, are of standard pipe fittings, which may be of any suitable size, and that they may be arranged to suit various stove constructions. They are preferably arranged so that the T joints 27 will be substantially adjacent the center of the stove parts. Two arrangements of the connector and the stove parts are shown in Figs. 3 and 4, and it is obvious that they may be assembled to either of these positions at the factory, or upon original assembly, and that at any time thereafter they may be reversed or changed to another arrangement. It will also be noted that by varying the length of a nipple, such as the nipple 31, the central duct of the connector 14 may be pitched in either direction and that the direction of pitch may be changed by shifting the arms to reverse the central duct.

The construction just described permits the stove units to be manufactured and shipped complete except for the mere connecting pipes.

Referring to the drawing, each unit may be equipped with its parts 23, 31-33, 32-24, and the T's 27, together with nipples 29, if desired. Thus constructed and supplied to the trade as a commercial article, it is only necessary upon installation to connect the supply pipe 22 with its appropriate T and insert in the assemblage the connecting line 25-26-24, the plug 28 being placed then in the open T end.

It is thought that the invention and many of its attendant advantages will be understood from the foregoing description, and it will be apparent that various changes may

be made in the form, construction and arrangement of the parts without departing from the spirit and scope of the invention or sacrificing all of its material advantages, the form hereinbefore described being merely a preferred embodiment thereof. 70

We claim:

In a stove the combination of a burner section and a broiler section arrangeable one at either side of the other, said sections being provided with fuel supply inlets at their rear, and a said section having a burner supply manifold at its front and connected to the fuel supply inlet of said section at the rear by a pipe passing through the section, and a pipe assembly at the rear of the stove for delivering fuel to said supply inlets, said pipe assembly consisting of parts adapted to be connected together in one relationship when said sections have one arrangement and in a different relationship when said sections have the reverse arrangement. 75 80 85
